United States Patent Office.

ARCHIBALD H. C. BARBER, OF CLINTON, ILLINOIS.

Letters Patent No. 60,666, dated January 1, 1867.

GRAIN DRYER.

The Schedule referred to in these Letters Patent and making part of the same.

TO ALL WHOM IT MAY CONCERN:

Be it known that I, ARCHIBALD H. C. BARBER, of Clinton, De Witt county, State of Illinois, have invented a new and useful Improvement in Grain Dryer; and I do hereby declare that the following is a full, clear, and exact description thereof, which will enable others skilled in the art to make and use the same, reference being had to the accompanying drawing, forming part of this specification, in which—

Figure 1 is a top or plan view of my improved grain dryer, parts being broken away to show the construction.

Figure 2 is a vertical longitudinal section of the drying kiln taken through the line $x\ x$, fig. 1.

Figure 3 is a vertical longitudinal section of the furnace taken through the line $y\ y$, fig. 1.

Figure 4 is a vertical cross-section of the drying kiln taken through the line $z\ z$, fig. 1.

Figure 5 is a vertical cross-section of the furnace taken through the line $x'\ x'$, fig. 1.

Similar letters of reference indicate like parts.

My invention has for its object to furnish an improved grain dryer by means of which grain may be thoroughly, evenly, and quickly dried. And it consists, first, in the combination of hollow rings and connecting pipes with each other and with a horizontal or vertical furnace for the purpose of heating air to be forced or driven into the drying kiln, or forced or driven through the rings and connecting pipes into the drying kiln; second, in the drying kiln, formed by combining an interior revolving perforated cylinder, constructed with interior longitudinal flanges or lifters, with the exterior, stationary, air-tight cylinders or drums, the whole being constructed and arranged as hereinafter more fully described.

A is the exterior drum or cylinder, which is stationary, and is supported in a slightly inclined position, as shown in fig. 2. This cylinder is made air-tight to prevent the escape of the heated air before it has passed entirely through the kiln or drying chamber A, and also to prevent the entrance of cold air to cool the kiln and retard the progress of the drying. B is the interior cylinder, which may be made of perforated sheet metal or woven or netted wire, as may be desired or most convenient. This cylinder is securely attached to the ends of the radial arms, b^1 , which radiate from the shaft, C, to which they are firmly attached. These arms should be sufficient in number and sufficiently near to each other to support the cylinder B and the grain which it may contain. The shaft C revolves in bearings in the ends of the exterior cylinder A, as shown in fig. 2, and motion may be given to it by any convenient power. To the ends of the radial arms b^1 are attached longitudinal strips or flanges, b^2 , extending almost the entire length of the said cylinder B, as shown in fig. 2. These flanges b^2 , as the cylinder B revolves, act as lifters to carry the grain with them in their ascent and allow it to fall back through the heated air in the cylinder, thereby thoroughly stirring it and securing its being uniformly and evenly dried. To the edge of the forward or upper end of the cylinder B is attached a flange, b^3 , projecting inward to prevent the grain from flowing or falling back and getting between the cylinders B and A. The grain is introduced into the cylinder B through the feed-pipe, D, in the ordinary manner; and after passing through the cylinder B, escapes, at the lower end of the cylinder A, through the pipe or spout, E; after which it is passed through another set of cylinders constructed in the manner described, where it is exposed to a blast of cold air, cooling it and bringing it into a proper condition for storage. The furnace, F, may be a horizontal furnace, as represented in the drawings, or it may be a vertical one, as the circumstances of each case may render advisable. f^1 is the grate, and f^2 is the fire-chamber of the furnace. G are hollow rings placed in the furnace and connected together by the connecting pipes, H, as shown in figs. 3 and 5, that is to say, if the induction pipe is connected with the lower part of the ring on one side, the eduction pipe is connected with the upper part of the ring on the opposite side, so that the air may be compelled to circulate through the ring before escaping therefrom. The number of rings G employed and their size will depend upon the capacity of the apparatus and the amount of work to be done. The air is introduced through the pipe I, and after passing through all the rings G, escapes through the pipe J, whence it is conducted through the pipe K, (shown in red in fig. 1,) and introduced into the drying kiln through the pipe L. The passage of the air through the furnace and kiln should be accelerated by a bellows, fan-blower, or some similar apparatus connected with either the pipes K or I, which may either exhaust or force or blow the air through the furnace, and blow or force it through the kiln, by which means the rapidity of the drying is much increased. The air, after passing through the kiln, escapes through the pipe M into the air, carrying with it the steam, &c., that has been driven off from the grain.

The bellows, fan-blower, or similar apparatus, is also used to blow or force the cold air through the drying kiln used for cooling the grain.

I claim as new, and desire to secure by Letters Patent—

The hollow rings G and connecting pipes H, constructed as described, in combination with each other and with the furnace of a drying kiln, substantially as described and for the purpose set forth.

ARCHIBALD H. C. BARBER.
